UNITED STATES PATENT OFFICE.

JOHN O'NEIL, OF NEW YORK, N. Y., ASSIGNOR TO HIMSELF AND R. A. SCHONEMAN, OF SAME PLACE.

DESIGN FOR SEWING-MACHINE FRAMES.

Specification forming part of Design No. 6,451, dated February 18, 1873.

To all whom it may concern:

Be it known that I, JOHN O'NEIL, of the city, county, and State of New York, have invented a new and original Design for a Sewing-Machine Frame, of which the following is a specification:

Figure 1 is a side elevation, and Fig. 2 is a plan view, of the sewing-machine stand constructed according to my improved design.

Similar letters of reference indicate corresponding parts.

A is a short and narrow table, with a short and broad leg, B, on one side, and two legs, C, on the opposite side. These legs C extend

above the top of stand A perpendicularly for a short distance, and unite in one plate, which then curves downward at E to a right angle, and extends at F in a horizontal direction from the stand as far as needed for the particular uses for which the machine is made.

I claim—

The design for sewing-machine stand, as shown.

JOHN O'NEIL.
